CLAIM

The ornamental design for a set of daytime running lights, as shown and described.

DESCRIPTION

FIG. 1 is a front left perspective view of a set of daytime running lights (DLR) for a vehicle according to the present invention.

FIG. 2 is a front right perspective view of the set of daytime running lights shown in FIG. 1.

FIG. 3 is a rear left perspective view thereof.

FIG. 4 is a front view thereof.

FIG. 5 is a left side view thereof.

FIG. 6 is a top view thereof; and,

FIG. 7 is a front view of the set of daytime running lights shown in FIGS. 1-6, mounted on the front left end of a vehicle, with the vehicle shown in de-emphasized and half-tone portions so as to illustrate environmental structure. These portions form no part of the claimed design. More particularly, in FIG. 7, the inventive set of daytime running lights is shown within the broken line, and the elements shown outside the broken line form no part of the claimed design, but are instead included to show environmental aspects thereof. FIG. 7 also shows another set of daytime running lights mounted on the front right end of the vehicle, as a mirror image of the daytime running lights shown in FIGS. 1-6, with respect to the longitudinal axis of the vehicle.
